ADJUSTABLE ARMING MECHANISM

Jacob Rabinow, Washington, D. C., assignor to
the United States of America as represented
by the Secretary of War

Application October 25, 1946, Serial No. 705,788

5 Claims. (Cl. 102—81.2)

(Granted under the act of March 3, 1883, as
amended April 30, 1928; 370 O. G. 757)

1

The invention described herein may be manufactured and used by or for the Government for governmental purposes, without the payment to me of any royalty thereon.

The present invention relates to projectile and bomb fuzes and, more particularly, to delayed arming mechanisms therefor.

Many conventional fuzes are provided with means for delaying the arming of the fuzes until the projectile or bomb has traveled a predetermined distance. It is a disadvantage of such arming delay devices, however, that they are not adjustable to any great extent to meet the requirements of varying conditions of use, nor are they able to provide very long arming delays. For the purpose of rendering conventional fuzes adaptable to the varying needs encountered, there is disclosed in my copending application, Serial Number 705,787, filed October 25, 1946, a device for enclosing the nose of a standard fuze to render the arming mechanism of the fuze inoperative for a predetermined distance or flight, said device being provided with means to remove the device from the nose of the fuze in flight after a predetermined distance of travel which may be varied over a wide range.

The present invention is an improvement upon the invention disclosed in my said copending application and has for its principal object the provision of a more compact and simplified construction to accomplish the purpose of the device of my prior invention.

More particularly, it is an object of the present invention to provide an adjustable device adapted to be attached to a standard fuze to provide an arming delay which eliminates the need for a cover for the fuze nose.

A further object is to provide a device that will be completely effective in its prevention of premature arming of the fuze, which may be firmly attached to the fuze and, at the same time, will release itself from the fuze without danger of malfunction.

The accomplishment of the above and other objects will be apparent from the following description of a specific embodiment of the invention shown in the accompanying drawings in which:

Figure 1 is a perspective view of the arming delay device attached to the guard ring of a standard fuze;

Figure 2 is a perspective view of the arming delay device as it is released from the fuze;

Figure 3 is a cross-sectional view taken along the line 3—3 of Figure 5;

Figure 4 is a cross-sectional view taken along the line 4—4 of Figure 5;

Figure 5 is a cross-sectional view taken along the line 5—5 of Figure 6;

Figure 6 is a cross-sectional view taken along the line 6—6 of Figure 5, except that the worm and gear are shown in disengaged position.

Referring to the drawings, the numeral 1 denotes the nose of a conventional fuze having an arming vane 2 rotatably mounted thereon and provided with a guard ring 3 supported on brackets 4.

The arming delay device of the present invention, generally denoted by the reference numeral 5, comprises a housing 6 adapted to be securely fastened to the guard ring 3 by means of bent-up projections 7 for engaging the lower edge of the guard ring 3 and a rotatable shaft 8 having a hooked end 9 for engaging the upper edge of the guard ring 3. A projection 10 on the housing 6, adapted to overlie the guard ring 3 stabilizes the connection afforded by projections 7 and shaft 8.

When the housing 6 is attached to the guard ring 3, as described above, it retains a pin 11 received through an aperture 12 in the guard ring in the position shown in Figure 1, whereby the post 11 extends between two of the blades of the arming vane 2 and effectively prevents the vane from rotating. A volute spring 13 secured to one end of the pin 11 urges the pin away from the guard ring 3 and, when the shaft 8 is turned to a disengaging position, also acts to separate the housing 6 from the guard ring 3.

35 A lever arm 14 is fixed on shaft 8 and adapted to turn therewith. A spiral spring 15 engaged at one end to the lever arm 14 and at the other end to the housing 6 normally urges the lever arm 14 into the position shown in Figure 2 in which 40 position the shaft 8 is rotated sufficiently to disengage its bent end 9 from the upper edge of the guard ring 3.

When the arming delay device 5 is attached to the nose of the fuze 1, the lever arm 14 is manually rotated to the position shown in Figure 1 where its free end may be received through a slot 20 in a cup shaped dial 16 mounted on a rotatable shaft 17 whereupon the dial may be rotated to retain the end of the lever arm 14, thus locking the housing 6 on the guard ring 3.

The shaft 17 on which the dial 16 is mounted is provided with a worm wheel 18 which is adapted to be driven by a worm 19 mounted on a rotatable shaft 20. Inasmuch as the dial end 55 of shaft 17 is supported in an elongated slot 21

in the housing 6, its weight will move the worm wheel out of engagement with worm 19. This facilitates the turning of dial 16 to a position for retaining the end of lever arm 14 and also for setting the dial for a predetermined flight distance as will be explained more fully hereinafter. After the end of lever arm 14 is received within dial 16, the upward force on lever arm 14 produced by the spring 15 lifts the dial 16 and end of shaft 17 to engage the worm wheel 18 with worm 19.

The shaft 20, and thus the shaft 17 and dial 16 are driven through a gear train consisting of rotatable shafts 22 and 23, worms 25 and 25', and worm wheels 26 and 27, by a vane 28 mounted on the shaft 23. It thus will be seen that as the vane 28 is rotated by the flow of air during flight of the projectile or bomb, the dial will be slowly returned by means of the speed reduction afforded by the gear train to the position shown in Figure 2 which releases the lever arm 14.

As explained above, the release of the lever arm 14 permits the spiral spring 15 to turn the arm and thus the shaft 8 to position shown in Figure 2 so that the hooked end of the shaft no longer engages the guard ring 3. Thereupon, the housing 6 and pin 11 are thrown outwardly away from the nose 1 of the fuze so that the fuze is then able to function in its normal manner.

Taking into account the speed reduction afforded between the vane 28 and dial 16 may readily be marked and calibrated to show the setting of the dial required to obtain a predetermined arming delay when attached to the fuze.

Due to the characteristics of the load on the vane 28 in relation to the relatively large vane area, there is very little air slip on the vane, whose rotation is therefore essentially a function of air travel rather than air speed. Hence the calibration and setting of the arming mechanism is substantially independent of the speed and is determined by the distance travelled. When my arming device is used on bombs which may be released from an airplane at various speeds, it can still be set for a predetermined distance of travel prior to functioning, which is another advantage of my construction.

In order to render the fuzed projectile safe prior to launching, I employ the customary arming wire, 31, which is passed through suitable holes in the casing and in pin 11, as shown in Figure 3, and which also obstructs vane 28. Immediately prior to launching, wire 30 will be withdrawn, and the device will then be ready for operation, as shown in Figure 1.

It will thus be seen that by the device of the present invention it is possible to give a standard fuze arming delay characteristics which may be varied over a wide range as desired. This greatly increases the versatility of standard fuzes and makes it practical to provide fuzes having the greatly varied characteristics required in combat. At the same time, the device is simple in construction and self-releasing from the fuze whereby subsequent operation of the fuze is not interfered with.

Having thus described an embodiment of the invention, it will be apparent that the device may be susceptible of modification by one skilled in the art within the scope of the invention, and all such modifications are intended to be covered in the appended claims.

I claim:

1. A device constructed and arranged to be at- 75 4

tached to the guard ring of a fuze to position an arming delay device thereon for a predetermined distance of flight comprising a projection having a hooked end for engaging one edge of the guard ring of a fuze, a rotatable shaft having a bent end constructed and arranged to be rotated into and out of engagement with the other edge of the guard ring, a spring member for rotating the shaft out of engagement with the guard ring, a lever secured to the shaft for rotating the shaft into engagement with the guard ring, locking means for retaining the lever in position for engaging the shaft with the guard ring, and means responsive solely to distance of air travel for unlocking said locking means during flight.

2. A device constructed and arranged to be attached to the guard ring of a fuze to position an arming delay device thereon for a predetermined distance of flight comprising a projection having a hooked end for engaging one edge of the guard ring of a fuze, a rotatable shaft having a bent end constructed and arranged to be rotated into and out of engagement with the other edge of the guard ring, a spring member for rotating the shaft out of engagement with the guard ring, a lever secured to the shaft for rotating the shaft into engagement with the guard ring, locking means for retaining the lever in position for engaging the shaft with the guard ring, an air vane, and a gear train connecting the air vane to the locking means to unlock same upon a predetermined distance of air travel.

3. A device constructed and arranged to be attached to the guard ring of a fuze to position an arming delay device thereon for a predetermined distance of flight comprising a projection having a hooked end for engaging one edge of the guard ring of a fuze, a rotatable shaft having a bent end constructed and arranged to be rotated into and out of engagement with the other edge of the guard ring, a spring member for rotating the shaft out of engagement with the guard ring, a lever secured to the shaft for rotating the shaft into engagement with the guard ring, a rotatable member for retaining the lever in position for engaging the shaft with the guard ring having a slot for receiving and releasing the lever, an air vane, and a gear train connecting the air vane to the rotatable retaining member for aligning the slot with the lever upon a predetermined distance of air travel.

4. A device constructed and arranged to be attached to the guard ring of a fuze to position an arming delay device thereon for a predetermined distance of flight comprising a projection having a hooked end for engaging one edge of the guard ring of a fuze, a rotatable shaft having a bent end constructed and arranged to be rotated into and out of engagement with the other edge of the guard ring, a spring member for rotating the shaft out of engagement with the guard ring, a lever secured to the shaft for rotating the shaft into engagement with the guard ring, a rotatably mounted member having a slot therein constructed and arranged for retaining the lever in position for engaging the shaft with the guard ring during rotation and for releasing the lever upon sufficient rotation to align the slot with the lever, an air vane, gear means for rotating the rotatably mounted member upon rotation of the air vane, and manually operated for disengaging the rotatably mounted member from the gear means.

5. The combination comprising a projectile

fuze, an arming vane rotatably mounted on said fuze, a guard ring on said fuze extending around said arming vane, means for interlocking said arming vane and guard ring to prevent rotation of the vane relative to the guard ring, a releasable holding member fixed to said interlocking means and engaging the guard ring so as to position the interlocking means in interlocking position, a second air vane rotatably mounted on said holding member, and lightly loaded and oriented so as to rotate as a function of forward air travel, a reducing gear train operatively connected with said second vane, means operable by said gear train to release said holding member after a predetermined rotation of said second vane, and means for forcibly propelling said holding mem-

ber and its associated elements forcibly away from said guard ring upon release of said holding member, to remove same and said interlocking means from the arming vane.
